FRANK C. NEWELL, OF WILKINSBURG, AND EDWARD H. DEWSON, OF EDGEWOOD PARK, PENNSYLVANIA, ASSIGNORS TO THE WESTINGHOUSE AIR BRAKE COMPANY, OF PITTSBURG, PENNSYLVANIA, A CORPORATION OF PENNSYLVANIA.

ELECTRIC BRAKE.

No. 841,710.

Specification of Letters Patent.

Patented Jan. 22, 1907.

Application filed April 11, 1904. Serial No. 202,529.

To all whom it may concern:

Be it known that we, FRANK C. NEWELL, residing in Wilkinsburg, and EDWARD H. DEWSON, residing in Edgewood Park, in the county of Allegheny and State of Pennsylvania, citizens of the United States, have invented a certain new and useful Improvement in Electric Brakes, of which the following is a specification.

This invention relates to electric brakes for cars in which the motors are adapted to be connected up as generators in a local brake-circuit; and the principal object of the invention is to provide an improved braking-controller and circuit connections whereby the current in the brake-circuit may be more readily and effectually controlled by means of a shunt around the fields of the generators having an automatically-operated opening and closing device and manually-operated means for varying the resistance in said shunt-circuit.

Another object is the provision of additional holding and priming points and circuit connections, whereby in certain positions of the braking-controller the line or power current may be utilized for energizing the brake-magnets or for priming the fields of the generators preparatory to the closing of the local generator-circuit; and still another feature of the invention comprises an improved arrangement of fuses so located with reference to the shunt-circuit as to permit the blowing out of the connection across the armature-leads on either side of the shunt-circuit connection.

In the accompanying drawings, Figure 1 is a diagram showing the contact-points and circuit connections of an ordinary car equipment of two motors and a running-controller with our improved braking-controller applied thereto, and Fig. 2 shows a series of diagrams illustrating the circuits corresponding with the various positions of the braking-controller.

Our invention is designed to be used in connection with any of the usual electric-car equipments, and for the purposes of illustration the same is shown as applied to the ordinary two-motor equipment having a standard series-parallel running-controller C and reversing-switch D.

According to the preferred construction the braking-controller comprises two movable parts or switches B and K, carrying different sets of movable contacts, the latter being adapted to occupy either one of two positions for running or for braking, respectively, and the switch K being so connected mechanically with switch B that the movement of the latter from its off position to its first braking position, (marked a,) or vice versa, operates automatically to throw the switch K to its braking position or to its running position, respectively.

Heretofore electric-car equipments have been provided with a braking-controller adapted to cut off the line or power current and to connect up the motors to operate as generators in a local circuit containing brake-magnets, the current being controlled by a variable resistance in said circuit. In addition to this our improvement provides a shunt-circuit containing a variable resistance around the fields of the generators when operating to supply current to the brake-circuit, said shunt-circuit being opened or closed by a voltage-regulator, the coil of which is located in the main brake-circuit, and the variable resistance in the shunt-circuit being controlled by additional contact-bars on the braking-controller. In order that the car may be held on grades after being stopped and the generators have ceased to generate current in the brake-circuit, the braking-controller may be provided with additional contact-points in either its initial position or final position, or both, for supplying line-current to the brake-magnets, and the line-current may also be utilized to prime the fields of the generators in the initial braking position of the braking-controller for the purpose of insuring the rapid building up of current in the local brake-circuit when the same is closed by further movement of said braking-controller. All of these features are embodied in our improved braking-controller and circuit connections, which will now be more fully described in detail.

Referring to Fig. 1 and considering the braking-controller B to be in its off position with switch K in position marked "running," the reversing-switch D in its forward position, and the running or power controller C moved

- to its first running position, the course of the current from trolley T or source of power will be as follows: to the initial bar of the controller C, thence to first resistance-bar and lead 5 R' through main resistance R and by lead R — to switch K, thence by contact-bars 22 20 and 23 25 to lead R C and to 19 on reversing-switch D, connecting-bar 4 to lead A', through armature A of motor No. 1, lead A A' to reversing-switch D, connecting-bar 3 and lead F' to F' C on switch K, connecting-bar 21 and lead F' M through field F of motor No. 1, lead E' to connecting-bars on running-controller C and lead 15 to reversing-switch D, connecting-bar 2 to lead A² of armature of motor No. 2, lead A A² to reversing-switch, connecting-bar 1, lead F² to F² C on switch K, connecting-bar 24 to field of motor No. 2, lead E² to switch K, and by contact-bar 26 to 10 ground G. Further movements of the running-controller C serve to vary the resistance and to connect the motors up in parallel, the operation of which is well understood by those familiar with the art. When it is desired to stop or check the speed of the car, the running-controller C is thrown to its off position and the braking-controller B is moved to its first braking position, (indicated by the dotted line a.) During this 15 movement the switch K is automatically thrown to its position marked "braking." The line-current from the trolley T then flows through the preliminary resistance T R to T S on switch B, cross connections 44 and 43 to lead B', which is the same as R', through the main resistance R, lead R — to switch K, connecting-bars 16 and 17 and leads F' C and F² C to reversing-switch D, connecting-bars 3 and 1, leads A A' and A A² through the armatures of the motors in parallel, leads A' and A² back to the reversing-switch, connecting-bars 4 and 2 to leads 19 and 15 to R C and 15 C on switch K, to the respective connecting-bars 47 and 18 to F' M and F² M, through the fields of the motors in parallel, leads E' and E² to switch K, contact-bars 14 and 49 to lead B C through coil O of blow-out magnet and through coil V of voltage-regulator to the main brake-magnet coils H, thence by lead B — to switch B, contact-bar 45, lead G' through coil O' of blow-out magnet, and secondary coils H' of brake-magnet to ground G. This is the circuit represented in the first diagram of Fig. 2 corresponding to position a. 20 In this position the shunt-circuit around the fields of the motors is open and has no effect, the line-current being passed through the field-coils of the motors to energize the same preparatory to closing the local brake-circuit. 25 When the braking-controller is moved to its next braking position, (marked b,) the contact-points for the line or trolley connection are cut out and the motors are connected up in parallel in the closed local brake-circuit, 30 the shunt-circuit around the fields also being

closed with no resistance. As the motors are then driven by the momentum of the car, they act as generators, and current flows from the armatures of both motors by respective leads A' and A² to reversing-switch 70 D, contact-bars 4 and 2, respectively, to leads 19 and 15, to R C and 15 C on switch K, by contact-bars 47 and 18 to F' M and F² M and the fields of the respective motors, thence by leads E' and E², contact-bars 14 and 49 the 75 two branches of the current unite at switch K in lead B +, passing through coil O of blow-out magnet and coil V of voltage-regulator to the main brake-magnet coil H, lead B — to bars 30 and 29 of braking-controller B, lead B', through main resistance R, lead R — to switch K, where the current divides on bars 16 and 17 to F' C, and F² C, thence to F' and F² on reversing-switch, and by contact-bars 3 and 1 to return-leads A A' and A A² of the 80 respective motors, thus completing the circuit, as indicated in the second diagram (position b) of Fig. 2. In this position at ordinary speeds the current immediately builds up sufficiently in the coil V of the voltage-regulator to close 85 the switch P, thereby closing the shunt around the fields of the generators through leads L' and L², which form an equalizing connection across the field-leads of the generators, thence by S' to contact-bars 39 and 40 on 90 the braking-controller B and lead S to B +. As there is little or no resistance in the shunt for this position, the fields of the generators are weakened to prevent an excessive current being built up in the brake-circuit. If a 95 stronger braking-current is desired, the braking-controller may be moved to the next position, (marked c,) in which all of the circuit connections are the same as in position b, except that the shunt connection is broken at S' and closed at S³, thereby inserting a certain amount of the shunt resistance S R in the shunt-circuit and to that extent increasing the strength of the fields and the current in the brake-circuit. A further movement of 100 the braking-controller to position d serves to open the shunt connection S³ and includes all of the resistances S R in the shunt-circuit, thereby further strengthening the fields by sending through the same nearly the entire 105 current of the brake-circuit. Further movement of the braking-controller to the successive positions e to l serves to cut out successive sections of the main resistance R, as will be readily understood by referring to contact-bars 27 to 36 and contact-fingers B' to B⁹ of the braking-controller B. In the next position (marked m) the bars 37 and 40 are disconnected from contact-fingers 53 and S, thereby entirely opening the shunt-circuit 110 and maintaining the generators in the closed local circuit with the brake-magnets and no resistance, which is the position for a maximum braking effect. In making a full stop the braking-controller is usually brought to 115

this latter position at the final portion of the stop, and then as the current ceases when the car stops the brake-magnets may not be able to hold the car in case the stop is made upon 5 a grade. It is therefore desirable to be able to supply the brake-magnets with current from another source at this point, and with our improved braking-controller this may be done by moving the same to the additional 10 position *n*, in which the bars 41 and 42 connect with contact-fingers G' and T S, thereby supplying current from the line or trolley T, through supplemental resistance T R, to coil O' of blow-out magnet and supplemental 15 brake-magnet coil H' to ground G. Either position *a* or position *n* may be used as holding-points for supplying the brake with current from an auxiliary source of power.

Another feature of our invention relates to 20 the arrangement of the fuse-blocks f' and f'', which are located in the equalizing cross connection between the motor-field leads one on each side of the branch connection to the shunt S, whereby when the shunt is cut in by 25 the closing of the switch P of the voltage-regulator V should either fuse blow out by an excessive current through the equalizer the other motor or generator would still remain connected up through the other fuse-block 30 with the shunt for controlling the speed of the car. The voltage-regulator V is designed to close the switch P of the shunt as soon as the fields of the generators have built up sufficiently to generate the desired current to properly control the brake-magnets, 35 and for light braking effects the resistance in the shunt, and correspondingly the strength of the fields, is manually controlled by the positions *b*, *c*, and *d* of the braking-controller. 40 It will now be seen that by means of our improvement the line-current may be used in the first or preliminary position of the braking-controller for both priming the fields of the generators and for energizing the brake-magnets, 45 so that as the controller is further moved to its successive positions, including the shunt-contact connections, the fields will be sufficiently energized to rapidly build up a current of sufficient strength to properly control the brake and close switch P of the automatic voltage-regulator in the shunt. The 50 use of the voltage-regulator insures the building up of the fields of the generators to give sufficient current for braking at all speeds.

When the braking-controller is first thrown to any of its braking positions in which the shunt contact-points are engaged, it will be seen that if there was no means for temporarily maintaining the shunt open the fields of 55 the generators would be very slow in building up and generating sufficient current for the brake-circuit; but with our improved arrangement, including the automatic voltage-regulator, the switch P of the shunt remains 60 open temporarily, thereby at first diverting

all the current through the fields and causing the same to build up promptly and generate sufficient current to control the brake-magnets, at which time the shunt is then automatically closed, as before described.

Having now described our invention, what we claim as new, and desire to secure by Letters Patent, is—

1. The combination with one or more generators adapted to be driven by the momentum of the car, of a braking-controller for connecting up the generator or generators in a local brake-circuit, and having contact-points for controlling a shunt around the fields of the generators.

2. The combination with one or more generators adapted to be driven by the momentum of the car, of a braking-controller for connecting up the generator or generators in a local brake-circuit, a main resistance for the brake-circuit, a shunt-circuit containing a variable resistance around the fields of the generators, and contact-points on the braking-controller for varying the resistance in both the main brake-circuit and the shunt.

3. The combination on an electric car of one or more motors, a running-controller, a braking-controller for connecting up the motors to act as generators in a local brake-circuit, said braking-controller being provided with contact-points adapted in one position to supply line-current to the fields of the motor-generators and in another position to close a shunt around the fields of the generators.

4. The combination with one or more motor-generators, of a braking-controller having contact-points adapted in one position to supply current from the line to the fields of the generators, and in further positions to close a shunt of variable resistance around the fields of the generators and to control the resistance in said shunt.

5. The combination with one or more motors and a running-controller of a braking-controller for connecting up said motors to act as generators in a local brake-circuit, a brake-magnet and a variable resistance in said local circuit, the braking-controller having contact-points for controlling said resistance and other contact-points in the extreme position for supplying line-current to the brake-magnet.

6. The combination of one or more generators adapted to be driven by the momentum of the car, a local brake-circuit, a braking-controller having contact-points for controlling a shunt around the fields of the motors, and an automatic voltage-regulator located in the local circuit for closing the shunt when the strength of the generated current is sufficient to operate the brake.

7. The combination of one or more generators adapted to be driven by the momentum of the car, a local brake-circuit, a main

resistance and a brake-magnet in said circuit, a shunt containing a variable resistance around the fields of the generators, a braking-controller having contact-points for controlling the resistance in both the main circuit and in the shunt, and an automatic voltage-regulator operated by the current in the local circuit for closing the shunt when the current is of sufficient strength to operate the brake-magnet.

8. The combination of two or more generators adapted to be driven by the momentum of the car, a braking-controller adapted to connect said generators up in parallel in a local brake-circuit with an equalizer connection across the field-leads, and a shunt around said fields connected to said equalizer, said braking-controller having contact-points for controlling said shunt.

9. The combination of two or more generators adapted to be driven by the momentum of the car, a braking-controller adapted to connect said generators up in parallel in a local brake-circuit with an equalizer connection across the field-leads, and a shunt around said fields connected to said equalizer, fuse-blocks located in said equalizer on each side of the shunt connection, said braking-controller having contact-points for controlling said shunt.

In testimony whereof we have hereunto set our hands.
